METALLIC SHINGLE

Ernest Bussey, Birmingham, Ala., assignor to
Sta-Eite Corporation, a corporation of Ala-
bama

Application January 6, 1939, Serial No. 249,598

11 Claims. (Cl. 103—17)

My invention relates to a metallic shingle and constitutes an improvement on the shingle forming the subject matter of Letters Patent 2,142,996, issued to me on January 10th, 1939, wherein I 5 show a shingle of approximately square stock, which is adapted to be laid with a diagonal normal to the eave, has its upper and lower tips truncated, and has approximately the metal thus cut away at the tips forming offset nailing ears at 10 each of the side corners of the shingle, as laid. In the center of this shingle are formed a series of vertical beads intended both to stiffen the shingle body and to provide a raised or relief configuration that would neutralize the plain, 15 flat effect of the shingles in the roof.

While this patented shingle is successful in its method of application and in its coverage, yet I have found that the following features of improvement are desirable, viz; to produce more pronounced deformation of the shingle body so as to increase its shadow line effect; to preliminarily crimp the stock with very fine corrugations to soften its effect, reduce light reflection, permit the requisite deformation without distortion of the shingle, and provide ventilation throughout lapped areas; to arrange the crimped corrugations so that they traverse the lapped area in the direction which will enable them to check, trap, and discharge out of the lap area any moisture seeking to creep transversely inwardly across the lapped joints in the roof; to design the shingle with its stiffening beads laid within its marginal lap areas and parallel with adjacent edges, and so matched that they not only facilitate the quick laying and accurate centering of the shingles, but also have the important effect of forming dams that run across the crimped corrugations in the lap areas and provide means to prevent any tendency of water to be blown in, or to move, responsive to capillary attraction, transversely across the lap areas so as to produce a leak; and finally to modify the design of the nailing ears so as to provide them with rounded tips and with vertically aligned notches in the horizontal and diagonal edges of each ear, the round tips reducing possible injury to the roofers and the notches having advantages which will be later pointed out.

My invention also forms a continuation in part of my patent aforesaid in respect of the provision of seats struck up in nailing ears to conform to and receive the lock lips on the shingle butts.

In the drawings:

Fig. 1 is a plan view of a shingle in which the fine crimped corrugations are omitted, because of the scale of this figure they would present a confusing shaded aspect.

Fig. 2 illustrates a portion of a roof laid with the shingles as illustrated in Fig. 1, with one shingle shown detached and ready to be moved 60 diagonally downwardly into position on the roof.

Fig. 3 is a fragmental view showing a corner portion of the shingle in full size with the crimp corrugations appearing.

Fig. 4 is a cross sectional view taken on the line IV—IV of Fig. 3.

Fig. 5 is a section on the line V—V of Fig. 3 with the overlying shingle butt shown dotted in.

Similar reference numerals refer to similar parts throughout the drawings.

In the embodiment of my invention in the 10 shingle design shown in the drawings, I show a metallic shingle having a substantially rectangular body with its lower butt tip truncated at 10 and its upper tip at 16, the shingle being so cut from stock that the metal displaced by these truncations is used to present at the side corners of the shingle reversely disposed offset nailing corners 12 and 13, the upper horizontal edge of the corner 11 and the lower horizontal edge of the corner 12 lying parallel with and equi-distant 15 from the interposed horizontal diagonal of the shingle. These shingles are laid as shown in Fig. 2 with a marginal lap only and the main central body portion of the shingle lying between its marginal lap areas is struck up at 14 to produce a pronounced shadow line effect in the roof as laid. This raised portion 14 is truncated at its upper and lower edges to leave corresponding plain surfaces 15 where the upper and lower tips overlie and underlie the nailing ears 12 and 13 in 20 25 30 35 and 13 are rounded at 20 to avoid provision of a sharp point and prevent injury in handling. All of the beads 16 are similar in size and are correspondingly placed along the shingle edges in symmetrical relation to the horizontal diagonal of the shingle body 14 so that they not only permit the reversibility of the shingle, but they will always match and interfit with the corresponding ribs in the side lap areas of underlying shingles 10 and thus will produce three important effects: namely, that of accurately centering the shingles by means of the interlocking of these ribs as they are laid so that the shingles cannot get out of line and can be laid rapidly and accurately with 15 out a preliminary lining of the roof; that of providing spaced dams to check the travel of water across the lapped areas of the shingles as laid; and that of both stiffening the edges and increasing the ornamental effect of the shingle. 20 The outer bead will check the ingress of water right at the outer edge of the shingle exposure and the inner beads form a second dam so displaced from the outer beads that any water that finds its way into the side laps inwardly of the 25 outer beads will be checked at the base of the inner beads and will not escape inwardly so as to produce a leak. Further, these beads being similar in size do not have surface contact throughout their joint and thus they provide a 30 means to check any capillary action and provide an inclined trough or channel along which any water gaining access to either of the bead joints will be guided down and discharged onto the plain area 15 of the subjacent shingle. 35 As a means for enabling the shingles to interlock themselves positively and accurately into position by means of relatively small beads, without being deformed as the result from the striking up of these beads 16 or of the center portion 40 14, and also as a means for enhancing the appearance of the roof and of further checking the lateral ingress of water across the lapped areas, I form the shingles from finely crimped stock, the original corrugations preferably having a maximum depth of approximately one thirty-second 45 of an inch and being formed on centers approximately three-sixteenths of an inch apart. The corrugations are preferably disposed so as to lie parallel with the vertical diagonal of the shingle. 50 In view of the very fine character of these corrugations 21 it was thought impractical to show them over Figs. 1 and 2, but they have been shown in exaggerated form in Figs. 3 and 4, it being noted that in the operation of stamping out the shingles to form the beads 16 and raise the 55 under panel 14 the corrugations will be stretched along the edges of such deformations and made substantially less pronounced than in the original stock. These corrugations 21 being disposed vertically or so as to serve to check water seeking to traverse the lapped area, will themselves form very small traps or drainage channels (see Fig. 4) through which any moisture, seeking to creep across the lapped area, will be trapped and diverted downwardly. These corrugations 21 60 not only soften the effect of the roof, but they supply the necessary amount of stock to enable the beads 16 and the center deformation 14 to be struck up without injuring the metal or breaking the spelter coat on the singles and without 65 warping or adversely deforming the shingle body, this being important not only to enable the beads of lapping shingles always to match but also to permit a very pronounced deformation in the central area 14, which in the laid roof will produce 70 75

distinctive shadow lines and thus enhance the ornamental appearance of a roof laid with these shingles. These corrugations 21 afford only line contacts between the lapped shingle surfaces and so will amply ventilate these joints and thus pre- 5 serve the shingles.

The deformation 14, like all other parts of the shingle lies symmetrical with respect to its horizontal diagonal, thus permitting it to be inverted and the parts of cut shingles to be used so 10 as to reduce the waste in laying the roof in the manner described fully in my patent aforesaid.

In Fig. 2 I have illustrated the manner of laying a roof with my improved shingles, and here I show a starting strip 22 laid along the eave and a 15 starter course of half shingles 24, cut, if desired, with enough additional stock along their bottom edges to be turned in under and form an interlock with the edge of the starting strip, and when thus laid the diagonal center line of the half 20 shingle will match with the lower edge of the starting strip. After this starting course is laid and secured by nails through their top lips 19, the first course of full sized shingles is laid, this being quickly accomplished by matching the 25 beads 16 on the sides of their butts with the beads 16 of the starting course shingles, in doing which the horizontal edges of the full sized shingle ears 12 are matched with the edges 11 of the subjacent 30 starter shingle 24 and the corners of their respective notches 17 are matched with the near corner of said edges 11. As seen in Fig. 3 this brings the diagonal edges of the meeting ears 12 and 13 of the first course shingles into engagement, whereupon their butt edges 10 are bent to 35 lock under the half shingles and starter strip.

The matched ears 12 and 13 of adjacent pairs of whole shingles in the first course, as shown in Fig. 3, form foundations, each of which overlies the upper tip area 15 of a subjacent half 40 shingle 24 and will underlie the butt tip area 15 of a superjacent whole shingle of the second course when laid.

The exposed butt tip of each shingle above the first course has its lip 19 bent back under and 45 engaged in a seat 19a formed in the center of the horizontal bottom edge of the ear 13 of its subjacent foundation when its edge 10 matches the under edge of said ear and its corners match with the notches 17 and 18 in the ears of the sub- 50 jacent shingles.

To match the seats 19a formed on the ears to receive the lock lips 19 I form on the butt tips opposite the lock lips 19 complementary raised portions 19b which will match with the seats 19a 55 and permit the butts to lie flush with the under ear edge and to ride over the upper ear deformation 19b where the resulting slight separation of the metal surfaces will not produce any adverse condition in the roof. The seats 19a play an im- 60 portant part in facilitating the quick and accurate centering of the shingle butts on their underlying foundations because it is easy to catch the lip 19 in its seat 19a and when it is so caught it is positively centered with respect to the sub- 65 jacent ear 13 and is in position for its beads to match with the beads of the subjacent shingles. Thus, by engaging 19 and 19a, aligning the edges 10 and 11 with the ears and their notches 17 and 18, and matching the beads 16, a roof can be very 70 rapidly and accurately laid and the shingles can- not get out of line, because if they do it would be impossible to match the beads or to align the ears and notches with tips 10 and 11.

A roof laid with my improved shingles and in 75

the manner described will provide safely against leakage with so small a lap area that it will only require about 135 squares of the shingles to cover 100 squares of roof.

5 It is further to be noted that the employment of the crimped stock will reduce the glare and both soften and enhance the appearance of the roof as a whole, even though the corrugations 21 are very fine.

10 While in my patent aforesaid I claimed broadly the provision of centering elements that would inter-engage to lock the shingle butts to sub-
15 jacent ears, the provision of the lock lip seats 19a and deformation 19b were not specifically claimed in that case, not being so important there, as there were no beads 16 in the lap areas to be accurately centered as in the present case.

While I have shown my invention in but one form, it will be obvious to those skilled in the art 20 that it is not so limited, but is susceptible of various changes and modifications, without departing from the spirit thereof, and I desire, therefore, that only such limitations shall be placed thereupon as are imposed by the prior art 25 or as are specifically set forth in the appended claims.

What I claim is:

1. A metallic shingle having side nailing corners and tapering end portions, said shingle 30 having matching beads struck up in its side lap areas which are formed of finely crimped stock with its corrugations running in a direction to check water seeking to traverse a lap area and designed to allow for the bead deformation 35 without distortion of the shingle.

2. A metallic shingle having side nailing corners and tapering end portions, said shingle having matching beads struck up along its side lap areas and being formed throughout its surface 40 areas lying substantially level of finely crimped stock defining corrugations running normal to a horizontal diagonal line through the side nailing corners and at an angle to said beads.

3. A shingle according to claim 1, in which 45 the central area lying within the marginal lap areas of the shingle as laid is formed of firmly crimped stock and is substantially deformed to produce a center panel raised sufficiently to provide a distinct shadow line effect from the 50 shingle as laid on a roof.

4. A shingle according to claim 1, in which substantially the whole central area lying within the marginal lap areas of the shingle is struck up from crimped stock to provide a polygonal 55 raised substantially flat panel designed and arranged to produce a distinct shadow line from the shingle as laid on the roof, said deformation and marginal beads being symmetrical with respect to said horizontal diagonal of the shingle, 60 to permit the latter to be reversed.

5. A metallic shingle having side nailing corners and symmetrical upper and lower tapered portions terminating in truncated tips, and corresponding beads which are struck up in the 65 shingle's side lap areas being adapted to match in adjacent overlapping shingles and disposed symmetrically with respect to a diagonal through said side corners, the nailing corners and lap areas being formed by crimped stock lying substantially in a common plane except where said

beads are struck up therefrom, said beads forming positive centering elements to properly align the shingles and being disposed to form a dam means to prevent the water traversing the crimped lapped area.

6. A metallic shingle formed wholly of finely crimped stock cut to provide, therefrom side nailing corners and reversely tapered upper and lower body portions, the corrugations in the stock lying normal to a horizontal diagonal through 10 nailing corners, a symmetrical raised central deformation, and symmetrical raised marginal deformations formed in the marginal lap areas of the shingle whereby the shingles can be positively matched and centered as laid on the roof, 15 said crimped shingle body lying in a common plane except for said raised deformation.

7. A shingle according to claim 6, in which substantially the whole body area of the shingle lying inwardly of its marginal lap areas is struck 20 up to form a flat central deformation raised sufficiently to give a pronounced shadow-line-producing exposure, said deformations being symmetrical with respect to the horizontal diagonal through the nailing corners to make the shingle 25 reversible.

8. A metallic shingle having truncated butt and tip and offset side nailing corners, centering notches adjacent to said corners, and the tips of the corners being rounded and an edge thereof 30 being adapted to align with an edge of a notch in an adjacent shingle in the same row as laid on a roof.

9. A metallic shingle having truncated butt and tip and offset side nailing corners, centering 35 notches adjacent to said corners, said notches at each corner comprising corresponding pairs of edges that are in vertical alignment and in parallelism respectively.

10. A metallic shingle formed of crimped stock 40 comprising upper and lower symmetrical tapered portions and side nailing corners, the corrugations lying vertical to a horizontal diagonal through said corners, said shingles having marginal lapped areas as laid on the roof, said areas 45 having formed in each a corresponding set of matching beads, which beads stop short of and leave plain the butt and tip areas of the shingles, said butts comprising each a lock lip adapted when laid in exposed position to engage under 50 a nailing corner of a subjacent shingle in the roof.

11. A metallic shingle having a generally square body with opposed reversible truncated upper and lower butts and with side nailing ears which 55 are adapted in adjacent shingles of a row to abut and provide a foundation shaped to receive the butt of an overlying shingle and to provide a horizontal matching edge for the overlying butt tip, matching beads symmetrically disposed in 60 the marginal lap edges of the shingle body, corresponding aligning lock lips projecting symmetrically from the center of both truncated butt edges, the lowermost lip being adapted to hook under the horizontal matching edge of the 65 subjacent shingle ear, and said matched butt tip and shingle ear edge having complementary center deformations which are adapted to interfit and accurately center the shingles as laid.
